JOSEPH REICHENBACH, OF NEW WESTMINSTER, BRITISH COLUMBIA, CANADA.

PRELIMINARY FUEL HEATING AND FEEDING SYSTEM.

1,085,160.

Specification of Letters Patent.

Patented Jan. 27, 1914.

Application filed September 20, 1912. Serial No. 721,414.

To all whom it may concern:

Be it known that I, JOSEPH REICHENBACH, a citizen of the Dominion of Canada, residing at New Westminster, in the Province 5 of British Columbia, Canada, have invented a new and useful Preliminary Fuel Heating and Feeding System, of which the following is a specification.

This invention relates to a means for heating 10 a liquid fuel to approximately its flash point before admitting it to the burner of a boiler and is designed as supplementary to the liquid fuel service of the boiler to enable the liquid fuel to be used for raising the 15 steam in the boiler.

In the customary practice, where the heavier oils are used as fuel, the oil is delivered under pressure to the burner of the boiler by a pump which is operated by 20 steam derived from the boiler. On starting up such a boiler the oil service cannot be used until steam is generated to the required pressure to operate the pump and a fire is usually built in the fire box to enable this to 25 be done. This practice is obviously inconvenient and occupies considerable time, and the invention, which is the subject of this application, has been devised to enable the oil as delivered to the boiler to be heated to 30 approximately its flash point before delivery to the burner. This supplementary oil heating system is used until a sufficient steam pressure is obtained in the boiler to operate the normal oil service pump and is 35 then cut out of action.

The invention is particularly described in the following specification, reference being made to the drawings by which it is accompanied, in which:

40. Figure 1 shows in general arrangement the application of the device to a single burner in the fire-box of a boiler, and Fig. 2, a vertical section to an enlarged scale of the primary heating coil.
45. In these drawings 2 represents the boiler and 3, 3^a, 3^b the pipe by which the fuel oil is delivered under normal service to the burner at 4, which normal service is under pressure derived from a steam operated 50 pump (not shown) of any approved kind. This normal service of oil under pressure is therefore dependent on the presence of a head of steam in the boiler and is not available on first starting up the boiler. The 55 device, which is the subject of this application, supplements this normal oil service and

is used only until the required steam pressure is attained. It consists of an oil heating coil 8 through which oil is circulated by a hand operated pump 6, the oil being derived by a pipe 5 from the oil service pipe 3, 3^a which delivers via its branch 3^b to the burner 4 of the boiler, a valve 13 being in this connection of 5 to 3^a, a valve 12 on the delivery branch 3^b to the burner of the boiler and a valve 11 between the sections 3 and 3^a of the service pipe outside of the connection at 10 from the heating coil 8.

The coil 8 is inclosed within a heat non-conducting casing 9 having a perforated top 18 from the center of which depends a baffle 19 comprising a series of bulb-like enlargements, around which a spiral groove 20 is formed which is designed to assist in circulating the hot gases around the coil. The 75 lower end of 19 terminates in a point in the center of a Bunsen burner 15 at the base of the coil 8. This burner 15 is served with a fuel gas in any convenient manner. In the drawing it is shown as deriving a distillate 80 gas from a reservoir 16 into which air is compressed by a small hand pump 17, the air volatilizing a light hydrocarbon distillate, such as benzin.

In use, when this pre-heating device is required to be used to raise steam in the boiler, the valve 12 is closed to shut the oil service from the burner 4 of the boiler until the oil is hot enough, and the valve 13 is opened admitting it to the coil. Air is compressed in the reservoir 16 with a few strokes of the hand pump 17 and the burner 15 is ignited. The oil in the pipe circuit 5, 6, 7, 8 and 10 is circulated by means of the hand operated pump 6 and passing through the coil 8 is heated therein. When the temperature of the oil in this circuit is raised approximately to its flash point, the valve 12 is opened to admit it to the burner 4 at which it may be ignited to generate steam in the boiler. 95 When sufficient steam pressure is generated in the boiler to operate the normal oil service pump (not shown) the gas is shut off from the burner 15, the valve 13 is closed and the pre-heating coil 8 is thrown out of use; the delivery of the oil to the burner 4 being conducted in the normal manner through the pipe 3 3^a, 3^b, by the action of the steam operated oil pump (not shown) that is actuated by the steam derived from 100 the boiler. A simple provision is thus made whereby steam may be initially generated in 110

a boiler pending the attainment of sufficient pressure to operate the service pump and effect the heating of the oil, and the device is one that can be conveniently introduced in an existing service without changing any of its parts, the provision being distinctly supplemental to it.

What I claim is:—

1. The combination with a steam generator, a main fuel burner coöperative therewith, and a main oil supplying pipe line to said burner; of a supplementary primary heating apparatus comprising an oil heating coil having its ends in communication with said pipe line, a pump for effecting circulation of oil through said coil, and means for heating said coil.

2. The combination with a steam generator, a main fuel burner in position to heat the generator, and a main pipe line that conveys the oil to said burner, of an oil heating coil having one end connected to said pipe line at one place, and the other end connected with said pipe line at another place, a shut-off valve in the heating coil pipe line circuit, a shut-off valve in the main burner pipe line, a pump in the heating coil pipe line for setting up a circulation of oil through said coil and the portion of said main burner pipe line between the places of connection of the same with the coil pipe line, and a means for applying heat to said coil.

3. The combination with a steam generator, a main oil burner in position to heat the generator, and a main pipe line that conveys oil to the burner, of an auxiliary pipe line connected to said main burner pipe line

and including a heating coil, said main burner pipe line and said auxiliary pipe line having a portion in common, a control valve in said main pipe line adjacent to the main burner, a second control valve in said main pipe line for shutting off the flow of oil to both the main and auxiliary pipe lines, a third control valve in said auxiliary pipe line, a means connected in said auxiliary pipe line for effecting oil circulation through said coil when said last named valve is open, and means for applying heat to said coil.

4. In combination with a steam generator, a main oil burner in position to heat the generator, and a main pipe line that conveys the oil to the burner, an auxiliary pipe line connected to said main burner pipe line and including a heating coil, said main burner pipe line and said auxiliary pipe line having a portion in common, a control valve in said main pipe line adjacent to the main burner, a second control valve in said main pipe line for shutting off the flow of oil to both the main and auxiliary pipe lines, a third control valve in said auxiliary pipe line, a means connected in said auxiliary pipe line for effecting oil circulation through said coil when said last named valve is open, and means for applying heat to said coil.

In testimony whereof I have signed my name to this specification in the presence of two subscribing witnesses.

JOSEPH REICHENBACH.
